UNITED STATES PATENT OFFICE.

GEORGE W. PRIEST, OF NEWTON, MASSACHUSETTS.

PROCESS OF DRYING VARNISHED SURFACES.

1,262,977.

Specification of Letters Patent. Patented Apr. 16, 1918.

Application filed June 10, 1911. Serial No. 632,346.

To all whom it may concern:

Be it known that I, GEORGE W. PRIEST, a citizen of the United States, residing at Newton, in the county of Middlesex and 5 State of Massachusetts, have invented an Improvement in Processes of Drying Varnished Surfaces, of which the following is a specification.

My invention relates to certain improvements in the process of and apparatus for manufacturing so-called patent leather. Heretofore it has been customary in manufacturing patent leather to coat the leather with a varnish made generally of linseed oil 10 and some Chinese glue boiled to the desired consistency. After the varnish has been applied the leather is placed in a drying room or oven, so-called, and left from ten to eighteen hours at a temperature varying 15 from 140° to 170° Fahrenheit. It is then removed from the oven. The varnish at this stage is tacky to the touch and must be exposed to a drying operation in the sunlight. Such drying operation requires the action of 20 the direct rays of the sun and cannot be carried on in dull weather or at night. It usually requires an exposure of from eight to ten hours. It is found in practice that the so-called drying process is better accomplished 25 in cold, clear weather than in hot summer weather. The humidity of the air interferes with the quickness of the process. From this it would appear that the ultra-violet rays play a very important part in 30 the operation.

Having these facts in mind, I have made use of artificial sources of ultra-violet rays and particularly the so-called quartz lamp which usually consists of a quartz container 35 within which are electrodes separated by a vapor path through which the electric current is passed. Such lamps are very efficient producers of ultra-violet rays, and thus are peculiarly adapted to the purposes of my invention. It is highly essential that the container shall be of quartz as the rays desired for my purposes would be cut off by an intervening glass.

My invention, therefore, may be said to 40 consist essentially, in the use of an artificial source of ultra-violet rays for affecting the varnished surface of the leather, and in the combination of apparatus therefor. In practice I have found that an exposure of

the varnished surfaces to the artificial ultra-violet rays produced by quartz lamps, accomplishes in two to six hours fully as great a result in the "drying" process as is obtained by a full day in the usual manner, that is to say, by exposure to the sun-light. Moreover, by my invention, it is possible to manufacture patent leather at all times of day regardless of the weather.

In some instances it may be desirable to use an atmosphere of ozone coincident with the treatment by the ultra-violet rays as the ozone appears to have some oxidizing effect. Usually, however, the use of ultra-violet rays alone is sufficient and produces the best results.

In the accompanying drawings, I have illustrated a general organization of apparatus for carrying out the invention.

Referring to the drawing, 10, 10, represent quartz lamps of known construction 75 adapted to produce large quantities of ultra-violet rays. These are shown as suspended in the central portion of a revolving frame, 20, upon which may be stretched the skins or hides having the varnished surfaces exposed to the direct action of the ultra-violet rays from the lamps. The frame may be revolved in any convenient way for the purpose of better insuring that all portions of the varnished surfaces shall receive an equal 80 amount of treatment. At the same time that the treatment is proceeding a current of air may be driven through the oven or room containing the revolving cage, as indicated by the blower, 40, having an outlet 90 pipe, 42, leading to the cage, and supplied by a pipe, 44, leading from tank, 43. Heat may be applied during the process either by heating the air delivered through the pipe, 42, or by heating coils, 30, arranged 95 within the drying room.

In some instances if it is desired to expose the skins to the action of ozone at the same time, then an ozonizer, 12, may be employed and so arranged that its products 100 will be liberated within the drying room.

It will be apparent that various different ways may be adopted for exposing the skins to the action of the artificially produced ultra-violet rays, and that above described is only typical.

I claim as my invention:

1. The method of finishing patent leather

which consists in directing artificial light rich in ultra-violet rays against the varnished surface thereby bringing about the required chemical changes within the varnish.

2. In the process of manufacturing patent leather, the method of "oxidizing" the varnished surface which consists in exposing the same to the action of a heated atmosphere and to light rich in ultra-violet rays.

3. The process of drying, setting and fixing patent-leather varnish which consists in exposing the varnished surface to the direct action of ultra violet rays of light in a drying room and charging the atmosphere of the drying room with ozone in excess of

that which is incidentally generated by the presence of the ultra violet rays of light.

4. The process of drying, setting and fixing patent-leather varnish which consists in subjecting it in a closed unventilated chamber to the action of ultra violet rays of light in the presence of ozone in excess of that which is incidental to the presence of the ultra violet rays of light.

In testimony whereof, I have signed my name to this specification, in the presence of two subscribing witnesses.

GEORGE W. PRIEST.
